Attorney

UNITED STATES PATENT OFFICE.

JOHN D. MERRIFIELD, OF ERIE, PENNSYLVANIA, ASSIGNEE TO REED MANUFACTURING COMPANY, OF ERIE, PENNSYLVANIA, A CORPORATION OF PENNSYLVANIA.

PIPE VISE.

Application filed September 16, 1922. Serial No. 588,587.

To all whom it may concern:

Be it known that I, JOHN D. MERRIFIELD, a citizen of the United States, residing at Erie, in the county of Erie and State of Pennsylvania, have invented new and useful Improvements in Pipe Vises, of which the following is a specification.

This invention is designed to facilitate the mounting of a pipe vise and also to provide it with pipe bending members. By this mounting the pipe vise may be readily secured to an anchored pipe and the bending members so secured with the pipe vise.

The invention is illustrated in the accompanying drawings as follows:—

Fig. 1 shows a plan view of the pipe vise.

Fig. 2 a bottom view of the vise.

Fig. 3 a section on the line 3—3 in Fig. 1.

1 marks the base of the vise, and 2 a movable jaw frame. The base has ears 3 over which extend the ears 4 on the frame, the two being locked together by pins 5. A latch 6 is pivotally secured to the frame and operates on a catch 8. A movable jaw 9 is mounted in the frame and actuated by a screw 10. Gripping dies 11 and 12 are secured to the jaw 9 and base 1 respectively in the usual manner. So far as described these parts are of ordinary construction.

A clamping plate 13 is secured to the side face of the base by means of clamping bolts 14. A clamping jaw 15 is arranged on the plate 13 and opposes the jaws 16, these being slightly staggered so as to more securely grip an anchored pipe 17. It will be noted that the clamping plate is arranged on the face of the base and this brings the supporting or anchored pipe closer to the work and reduces the leverage on the anchored pipe and the clearance necessary for the vise.

A bending surface 19 is arranged on the plate 13 and occupies a position at the opposite side of the anchor pipe from the jaws of the vise. A hook 20 opening outwardly from the base is cast on the base and forms a companion bending member operating in conjunction with the bending surface 19. A pipe 21 is shown in dash lines between the bending members. The base and clamping plate are provided with interlocking surfaces so that the bolts 14 are relieved from the bending strain on the clamp-

ing plate. As this strain is considerable this is important. This is accomplished in the present structure by forming a notch 22 in the base and extending a shoulder 23 into the notch.

What I claim as new is:—

1. In a pipe vise, the combination of a base; a fixed jaw on the base; a movable jaw; a frame carried by the base; means on the frame actuating the movable jaw; and a clamp on the side face of the base comprising a clamping member moving to clamping position in a direction at right angles to the direction of movement of the movable jaw.

2. In a pipe vise, the combination of a base; a fixed jaw on the base; a movable jaw; a frame carried by the base; means on the frame actuating the movable jaw; a clamp on the side face of the base comprising a clamping member moving to clamping position in a direction at right angles to the direction of movement of the movable jaw; and clamping screws extending from the clamp to the base.

3. In a pipe vise, the combination of a base; a fixed jaw on the base; a movable jaw; a frame carried by the base; means on the frame actuating the movable jaw; a clamp on the side face of the base comprising a clamping member moving to clamping position in a direction at right angles to the direction of movement of the movable jaw; clamping screws extending from the clamp to the base; a bending member on the base; and a bending member on the clamp.

4. In a pipe vise, the combination of a base; a fixed jaw on the base; a movable jaw; a frame carried by the base; means on the frame actuating the movable jaw; a clamp on the side face of the base comprising a clamping member moving to clamping position in a direction at right angles to the direction of movement of the movable jaw; clamping screws extending from the clamp to the base; a bending member on the base; and a bending member on the clamp, said clamp and base having interlocking surfaces.

5. In a pipe vise, the combination of a base; a fixed jaw on the base; a movable jaw; a frame carried by the base; means on the frame actuating the movable jaw; a clamp on the side face of the base comprising

2
ing a clamping member moving to clamping position in a direction at right angles to the direction of movement of the movable jaw; clamping screws extending from the clamp 5 to the base; an open bending hook arranged on the base and extending in a direction away from the frame and positioned away

from the edge adjacent to the jaw; and a bending member on the clamp co-operating with the hook.

10

In testimony whereof I have hereunto set my hand.

JOHN D. MERRIFIELD.
